UNITED STATES PATENT OFFICE.

JOHN S. MARDON AND LOUIS D. FAY, OF LOYALTON, CALIFORNIA.

WOODWORKING-MACHINE.

1,273,516.

Specification of Letters Patent. Patented July 23, 1918.

Application filed September 13, 1915. Serial No. 50,386.

To all whom it may concern:

Be it known that we, JOHN S. MARDON and LOUIS D. FAY, citizens of the United States, residing at Loyalton, in the county 5 of Sierra and State of California, have invented new and useful Improvements in Woodworking-Machines, of which the following is a specification.

This invention relates to wood working 10 machines, and has for its object to provide, in a device of this character, means to automatically receive, count and deliver piles of lumber stock ready for bundling or whatever operation is next desired.

15 The machine of this invention is adapted to be placed beyond a lumber or box board resawing machine, and the stock, (short boards or box shook) as they leave the resawing machine are received by the rolls of this machine, automatically counted, and placed in one of the carriers, which carrier, when the desired number of pieces have 20 been placed in it, automatically moves away and another carrier takes the place of the first one. The stock as it comes from the resaw is in a vertical or edge position and the carriers in moving along turn at right angles, placing the stock in a horizontal position and depositing it on a set of traveling 25 chains, which chains are adapted to deliver the stock to a table, or other place, for bundling or other operation.

30 One form which our invention may assume is exemplified in the following description and illustrated in the accompanying drawings, in which—

Figure 1 shows a side elevation of a machine embodying our invention.

Fig. 2 shows a plan view of the same.

40 Fig. 3 shows an end elevation.

Fig. 3^a shows a detail view of a convenient manner of hinging the buckets to the conveyer chains.

Fig. 4 shows a sectional view, taken on 45 line 4—4 of Fig. 2, and illustrates the counting and stacking mechanism.

Fig. 5 shows a detail of the adjustable connection employed in the counting mechanism for varying the number of pieces received in each pile.

Fig. 6 shows a side elevation of a portion of the feeding rolls and associated mechanism.

Fig. 7 shows a plan, sectional view of the 55 parts illustrated in Fig. 6.

Fig. 8 shows a skeletonized plan view of

the driving and actuating mechanism for the various parts of the machine.

Fig. 9 shows an elevation of the carrier operating parts and the controlling means 60 therefor.

Fig. 10 shows a plan view, in section, of the mechanism which holds the pieces of material in an upright position and guides them as they are being placed in the carriage. 65

Fig. 11 shows a detail of the automatically controlled locking device employed in connection with the carriers.

Fig. 12 shows a sectional view in detail of 70 the latch mechanism for the buckets.

Referring in detail to the form of our invention illustrated herewith, it will be seen that the plan of the device, as shown in Fig. 2, comprises, generally, a main frame 10, 75 upon which is a platform 11 covering one end thereof, and adjoining one corner of the platform and main frame is a supplemental frame 12 carrying feed rollers 13. Traversing the platform, at right angles to the line 80 of feed of the rollers, is an endless conveyer 14 supplied with a plurality of carriers 15, two of such carriers being shown in the present instance. These carriers are hinged at their forward ends to the conveyer chains, 85 any suitable form of hinge connection being employed, such as that illustrated conveniently in Fig. 3^a.

The shafting for the conveyer 14, as shown in Fig. 1, is triangular in arrangement and comprises a drive-shaft 16, at the forward end of the platform, an idler shaft 17 immediately below the shaft 16, and a second idler shaft 18 at the rear end of the platform, all carrying sprocket wheels 90 19 over which the conveyer chains 14 operate. The movement of this conveyer is intermittent and timed and the operation of the same will be described later.

The feed rollers 13 are four in number 100 and are arranged vertically in coördinate pairs; the rollers at one side being journaled upon a movable frame portion 20, as best shown in Figs. 6 and 7. The movable part 20 is yieldingly pressed toward the 105 stationary portion by a coil spring 21 made adjustable through a screw shaft 22 operated by a crank 23. Intermeshing spur gears 24 transmit movement from one roller to the other of each pair, while bevel-gears 110 25, at the lower end of each roller on the stationary frame, mesh with similar gears

on a drive-shaft 26 continuously operated from a power shaft 27.

The pieces of lumber are fed in successive order to the feed rollers singly or in any 5 desired number of thicknesses; the rollers spreading apart on account of their yielding connection to accommodate the different thicknesses. In practice the number of boards fed each time will be the same, the 10 particular number depending upon the size, capacity and adjustment of the resawing machine. The pieces of material are delivered by the rollers in a vertical position and means are provided upon the platform 15 11 for stacking the pieces into an adjacent carrier which for the time being is held in a stationary position above the said platform. The means for stacking the pieces into the carrier comprises a sliding dog 28, 20 best illustrated in Fig. 4. It is reciprocally movable upon the main frame 10 and projects through a slot in the platform 11 and traverses a path across the line of feed of the rollers 13. This dog has an intermittent 25 operation and is actuated by a pitman connection 29, with a wheel 30, carried upon an intermittently operated shaft 31. This shaft is driven through a friction cam pulley 32 which coöperates with a friction pulley 33 30 carried on a continuously operated shaft 34 journaled in shiftable bearings 35.

As shown in Fig. 8, a spring-pressed trip lever 36 locks the shiftable bearings in their outward limit of movement by engagement 35 with a pin 37 carried on one of the same, and contractile coil springs 38 tend normally to draw the bearings and shaft inwardly to cause engagement of the friction members.

For actuating the trip lever 36, we employ 40 a spring-pressed plunger rod 39 extending transversely of the main frame beneath the platform and connected with a fulcrum bar 40 at the opposite end of the frame, as best shown in Fig. 3, where the said bar appears 45 in elevation. A pull spring 41 tends to draw the bar 40 in a direction to push the plunger against the trip lever.

Referring to Fig. 2, it will be seen that the fulcrum bar is connected at its upper 50 end with a tappet lever 42 lying adjacent to the feed rollers and on its inner end is provided with a small roller or tappet 43 in such a position as to be engaged by the pieces of lumber as they pass through the feed 55 rollers.

The operation of the mechanism so far described will be as follows: Assuming that one of the carriers 15 is lying at rest in front of the feed rollers and the latter are 60 constantly driven to feed pieces of lumber thereto, each charge or feed of material will carry the free end of the lever 42 a slight distance forwardly, due to the roller 43 thereon engaging with the pieces of lumber. The opposite end of the tappet le-

ver will move backwardly, carrying the fulcrum arm with it and placing the pull spring 41 under tension, and when the charge of material has passed entirely through the feed rollers the tappet lever will be released, 70 allowing the fulcrum bar 40 to throw the plunger forwardly, striking the trip lever 36 and releasing the shiftable bearings 35, whereupon the springs 38 will pull the friction pulley into operative engagement with 75 the cam 32 and a complete rotation of the latter will occur, moving the sliding dog forwardly, carrying the boards or pieces of lumber with it and advancing the carrier one step, itself retracting leaving a space for 80 the reception of the next charge of material. The action of the cam 32 pushes the friction pulley 33 away from it as the cycle is being completed and the trip arm 36 will thereupon reengage with the pin 37 and retain 85 the friction members out of operative engagement.

Each of the carriers 15 comprises a bottom 44 in line with or below the lower ends of the feed rollers, a front side portion 45, an 90 adjustable stop arm 46 at the outer side thereof, and an adjustable overhead arm 47. The bottom of the carrier is slotted, as at 48, to admit the sliding dog 28. A guide bar 49, best shown in Fig. 10, is arranged 95 adjacent to the feed rollers, being pivoted at 50 to the platform 11 and normally pressed toward the conveyer by a spring 51. This bar is adapted to engage with the rear ends of the boards at its curved end 52, when 100 the former are being fed through the rollers, and retain them in upright position after they have left the rollers. The sliding dog thereupon moving the boards forwardly in a transverse direction the curved end of the guide bar 49 will insure the engagement of 105 the forward ends of the boards with the stop arm 46 of the carrier so that the pieces of the material are neatly compacted in piles with their ends flush.

The guide bar 49 is also provided with a pivoted hook 53, held normally projected beyond the inner face of the bar by a spring clip 54. This hook normally occupies a position such as to engage a rear corner of the 115 boards when the same have been moved forwardly within the carrier, thereby to prevent falling of the same as the sliding dog is retracted. When, however, the pile of boards is completed in the carrier a gravity 120 pawl 55, best shown in Fig. 1, adjustably mounted upon the overhead arm 47, drops into position to retain the boards within the carrier secure against falling rearwardly.

After the carrier has been filled with the 125 desired amount of material, it is necessary to actuate the conveyer to deliver it to dumping position and place the other carrier in position to be filled. For this purpose we provide automatic means controlled 130

by the quantity of material delivered to the carrier.

As shown in Fig. 4, this mechanism comprises a counting device consisting of a ratchet disk 56 carried on a shaft 56^a and operated step by step by a pawl 57 carried on a vibratile arm 58, which arm is actuated by a connecting rod 59 fixed to a strap 60 encircling an eccentrically mounted disk 61, carried on the intermittently operated shaft 31. A friction cam pulley 62 is carried on the conveyer drive shaft 16 and coacts with a friction pulley 63 on a continuously driven shaft 64 mounted at either end in shiftable bearings 65, as in the case of the shaft 34.

As shown in Fig. 9 the separation of the friction members 62 and 63 is controlled by a vertical plunger rod 66 carrying a keeper 66^a which abuts one of the bearings 65, being normally held thereagainst by a pressure spring 67. Pivoted to the rod 66 is a horizontal fulcrum bar 68 carrying a standard 69 in position to be engaged by a pin 70 on a disk 71 mounted on the shaft 56^a. When the shaft 56^a has made a complete revolution, the pin 70 strikes the member 69 on the bar 68, moving the latter downwardly and causing disengagement of the keeper 66^a from the bearing 65, and allowing the springs 72 to slide the shaft 64 into position where the friction members 62 and 63 will be engaged. The conveyer driving shaft, thereupon, will be driven once around or until the highest part of the cam 62 thereon moves the friction pulley 63 away to a position where it will be held by the spring-pressed keeper 66^a. This movement of the conveyer driving shaft will provide the necessary travel for the carriers.

It will be seen that each actuation of the sliding dog 28 will move the ratchet disk 56 one step. By the provision of the adjustable connection, as shown in Fig. 5, between the vibratile arm 58 and the connecting rod 59 the distance through which the ratchet wheel moves upon each actuation may be varied. Thus if it is set to be moved one tooth, there being ten teeth in the wheel, it is obvious that each pile of boards delivered to the carrier will consist of ten pieces, and by varying the adjustment to move the ratchet wheel two teeth at each step, the quantity of pieces in each pile will be decreased one-half. The connection there shown comprises a strap 72 surrounding the spaced bars of the vibratile arm and a transverse pin 73 carried on the connecting rod 59, provided with gripping means 73^a, in the form of a nut for retaining the strap upon the arm 58. Pin 72 is likewise adjustable upon the connecting rod 59, being provided with a central bearing 74 surrounding the rod and held in position thereon by means of a set-screw 75.

Next, we provide for the automatic dump-

ing of the carriers as they traverse the vertical run of the conveyers, so that the boards will be discharged flatwise upon a supplemental conveyer 76. The supplemental conveyer is designed to deliver the boards to any desired position and comprises, generally, an arrangement of endless belts or chains driven continuously from a shaft 77 carried on the front portion of the frame and operated by means of any suitable connection 78 with the power shaft 27. The opposite ends of the chains 76 run over idlers 79, arranged adjacent to the vertical run of the conveyer 14, and mounted upon longitudinally arranged supporting bars 80, secured to the front portion of the main frame. By providing a slot 81 in the front side of each of the carriers in line with one of the conveyer chains 76 and setting one of the ends of said front inside the ends of the boards, we secure a close coaction between the carriers and supplemental conveyers, and the latter being lower than the horizontal run of the former a quarter turning of the carriers takes place which leaves the boards carried thereby in a flatwise position when they meet the supplemental conveyers.

As the carriers turn over, the overhead arm 47 will hold the boards against displacement, and to release the same and allow the pile of material to be discharged, we provide an automatically unlocking hinge 82 therefor. This hinge is best shown in Fig. 11 and is releasable by engagement with a trip device 83 carried on one of the supports 80 near the path of movement of the overhead arm. This hinge comprises generally the usual plates 84 forming bearings 85 for a pin 86. The bearings are of irregular bore, for instance, partly circular and partly square, and the pin is also of irregular cross section, preferably square in part and circular in part. The pin is slidable within the bearings and in certain positions, with its square portion lying in a round portion of the bearings, a turning of the hinge can occur, but, normally, the square portion of the pin is interlocked with the square portion of the bearings on account of a pressure spring 87, so that no turning of the hinge can take place. The pin is provided with a device 88 to engage with the stop or trip 83 which moves it to pivotal position, and thereupon the overhead arm is free to swing out of the way of the passage of the pile of material as the latter is moved from the carrier by the supplemental conveyers.

The hinge just described is of the form shown and described in our Patent #1,166,702, dated January 4, 1916.

Inasmuch as considerable weight is thrown on the carriers in making the turn from horizontal to vertical position, we employ a supporting arm 89, adjacent to the

end of the horizontal run of the conveyers 14, slidably mounted upon the main frame. This arm is shown as normally held rearward by a weighted cord 90, and projects 5 over the bottom of the carrier, passing through a recess in the front of the carrier. As the carrier turns, the arm will be engaged by the bottom and moved forwardly, restraining the outward and downward 10 movement of the carrier and relieving the conveyer of much of the increased strain. The bottom of each carrier will engage with the supporting arm when in angular position and be steadied thereby until the recess 15 91 in said bottom portion allows the arm to be released, whereupon the weighted cord will return it to normal position. The weight on the cord should be almost heavy enough to counterbalance the weight of the 20 carrier and material. A bumper spring 92 is shown in connection with the slide arm.

It is obvious that the machine here described can be used for a variety of purposes, and while we have shown and described but 25 one form and application of this device, it is to be understood that many changes in the construction and arrangement of the several parts thereof may be resorted to without departing from the spirit of our invention as 30 disclosed in the appended claims.

Having thus described our invention, what we claim and desire to secure by Letters Patent is—

1. In a machine for bundling, counting 35 and delivering boards, an overturning carrier, means to feed the boards on edge in successive order to the carrier, said boards being received in an edgewise position by the carrier and on a horizontal plane and means 40 operative when a predetermined number of boards have been deposited on the carrier to move the latter to a position where the boards will be dumped on their flat sides.

2. In a machine for stacking boards, the 45 combination of a horizontally movable carrier, means for feeding boards endwise in vertical position to a point in front of the carrier, means controlled by the feeding mechanism for stacking the material fed thereby into the carrier, and means for delivering the carrier to dumping position when a predetermined quantity of boards 50 has been received therein.

3. In an attachment for a vertical resawing machine, a carrier, mechanism for delivering boards from the resawing machine on edge to the carrier, means for adjusting the capacity of said delivering mechanism, whereby to adapt it for different sized 55 charges, and means operative to convey the carrier to a distant dumping position when the same has been filled.

4. In a machine for stacking boards, the 60 combination of a carrier, feeding mechanism 65 to receive boards on edge and move them

endwise to position in front of the carrier, and means in association therewith for delivering and guiding the boards on edge into said carrier.

5. In a machine for stacking boards, the 70 combination of mechanism for feeding boards endwise in successive order, reciprocal means to receive boards delivered thereby and move them at right angles to the direction of feeding movement, and means for 75 controlling the operation of the reciprocal means, comprising a trip device actuated by the passage of boards through the feeding mechanism.

6. In a machine for stacking boards, the 80 combination of a carrier and feeding mechanism, and means to receive boards delivered by said feeding mechanism and move them laterally into the carrier, said means comprising a reciprocal device intermittently 85 operated and controlled by the passage of boards through said feeding mechanism.

7. In a machine for stacking boards, the combination of a traveling carrier intermittently operable, mechanism for delivering 90 boards thereto while the carrier is at rest, means in connection with the carrier for locking the boards within, automatic means for putting the carrier in operation when it has been filled, and means for automatically 95 dumping said carrier at a point distant from its filling position.

8. In a wood working machine, the combination of a carrier mounted upon an endless conveyer, means to feed boards therein, 100 a locking device for the carrier to retain the boards in position therein, and a trip device to actuate the lock when the carrier is moved to dumping position.

9. In a wood working machine, the combination of a carrier mounted on an endless 105 conveyer, means to feed boards thereto in upright position, and means for dumping the carrier at right angles to its filling position to discharge the boards in a flatwise 110 pile.

10. In a machine for stacking boards, the combination of a carrier, an endless conveyer for said carrier movable in a horizontal plane, means for feeding boards thereto on 115 edge, in a horizontal plane, at right angles to the line of movement of the conveyer, means to advance the conveyer in a step by step operation to permit the carrier to be filled with boards, a latch device actuated by 120 the advancing means, and driving mechanism controlled by the latch device to move the carrier to position for dumping when a predetermined quantity of boards has been received therein.

11. In a wood working machine, the combination of a traveling carrier to receive boards and turnable at right angles to dumping position, an arm overlying said boards when the carrier is in receiving position and 130

- 5 serving to retain said boards within the carrier when the latter is turned, locking means on said arm, and a trip device to release said locking means, when engaged thereby, to cause the carrier to dump its load.
12. In an attachment for vertical re-sawing machines, the combination of a horizontally movable, overturning carrier, means for feeding boards thereto from the re-sawing machine in a horizontal plane at right angles to the line of movement of the carrier, intermittently actuated driving mechanism for the carrier, and means for setting said driving mechanism into operation when a predetermined quantity of boards has been received in said carrier to move the latter to dumping position. 70
13. In a machine for stacking boards, the combination of a horizontally movable carrier, means for feeding boards thereto in a horizontal plane at right angles to the line of movement of the carrier, intermittently actuated driving mechanism for the carrier, and means for setting said driving mechanism into operation when a predetermined quantity of boards has been received in said carrier, said last-named means comprising counting mechanism, and a trip device actuated thereby, said trip acting normally to retain the driving mechanism in disengaged position. 75
14. In a wood working machine, the combination of a carrier, feeding mechanism therefor, means for stacking boards delivered by said feeding mechanism into the carrier, intermittently operated means for actuating said stacker, and controlling mechanism for the intermittent means comprising a lever actuated by the passage of boards through said feeding mechanism, a trip device normally holding the intermittently operating means out of gear, and a connection between said trip device and lever. 80
15. In a machine for stacking boards, the combination of a carrier, means for feeding boards thereto at right angles to the direction of movement of the carrier, mechanism for advancing the carrier to permit the same to be filled by successive charges of boards, said advancing mechanism comprising a reciprocating member to engage with the boards and move them forwardly into the carrier, thrusting the latter forwardly at the same time, intermittently operating mechanism for actuating the reciprocating member, a trip device to retain the actuating mechanism inoperative, and means operable by the passage of boards through said feeding means to release said trip device. 85
16. In a wood working machine, the combination of a bucket, an endless conveyer therefor movable about horizontal axes, means to fill the bucket with boards when on the horizontal run of the conveyer, means to dump the bucket when on the vertical run, and means engageable with said bucket at the beginning of said vertical run to take the increased strain from the conveyer. 90
17. In a wood working machine, the combination of a carrier to receive boards in edgewise position, an endless conveyer therefor having a vertical run, whereby to turn the carrier in such position as to dispose the boards therein in a horizontal position, and a supplemental conveyer coöperating with said carrier, when the boards in the latter are in a horizontal position, to receive the boards therefrom and deliver them to a distant point. 95
18. In a wood working machine, the combination of an endless conveyer, movable along a horizontal and a vertical run, a carrier thereon, means for feeding boards to the carrier in upright position when the carrier is on the horizontal run of the conveyer, means operative by the passage of boards through the feeding means to advance the carrier step by step, means operative when a predetermined quantity of boards have been received to move said conveyer to position where the carrier will be disposed on the vertical run thereof and means to dump the boards in a flat-wise pile when the carrier is in the latter position. 100
19. In a wood working machine, the combination of an endless conveyer movable along a vertical and a horizontal run, a carrier thereon, means for feeding boards to the carrier in upright position when the latter is on the horizontal run of the conveyer, means operative by the passage of the boards through said feeding means to move them at right angles into the carrier, means operative when a predetermined quantity of boards have been received in the carrier to move the conveyer to position where the carrier will be disposed on the vertical run thereof and means to dump the boards in a flat-wise pile when the carrier is in the latter position. 105
20. In a machine for receiving, bunching and delivering boards, an endless conveyer, a bucket thereon to receive the boards, means in connection with the bucket to lock the boards in place, and means operable to release the locking means when the bucket has been delivered to dumping position. 110
21. In a machine for receiving, bunching and delivering boards, an endless conveyer having a long horizontal run and a short vertical run, a bucket thereon arranged to be filled with boards, one on the horizontal upper run of the conveyer, means to lock the boards in place within the bucket, and means operative to release the locking means and permit the bucket to dump its contents when the latter is upon the vertical run of the conveyer. 115
22. In a machine for receiving, bunching 120
- 65

and delivering boards, an endless conveyer having a long horizontal run and a comparatively short vertical run, a bucket arranged to receive a stack of boards in vertical position when upon the upper horizontal run of the conveyer, means to retain the boards in place within the bucket, and means coöoperating with the retaining means to release the latter and permit the bucket 5 to dump its contents when the said bucket is disposed upon the vertical run of the con-

veyer, whereby the boards will be deposited upon their flat sides.

In testimony whereof we have hereunto set our hands in the presence of subscribing 15 witnesses.
